RESONANT CONTROL RELAY

Roy J. Wensley, Moylan, Pa., assignor to Westinghouse Electric & Manufacturing Company, East Pittsburgh, Pa., a corporation of Pennsylvania

Application September 16, 1936, Serial No. 101,008

1 Claim. (Cl. 250—27.5)

My invention relates to remote control systems of the type in which superposed frequency currents are applied to an alternating current power line for the purpose of controlling translating devices such as street lights, meters, or off-peak load apparatus.

Various systems of this nature have heretofore been proposed in which a bimetal or other thermal element is utilized to distinguish between a comparatively short application of the superposed frequency currents and a longer application, in order to effect opening and closing operations by means of superposed currents of the same frequency. In general, however, the receiving apparatus of such systems requires a comparatively large amount of superposed frequency energy in order to directly effect the operation of the thermal element or of an electromagnetic relay.

It is, accordingly, an object of my invention to provide a novel remote control system of the type indicated above, in which the receiving apparatus shall require a minimum amount of superposed frequency energy.

Another object of my invention is to provide a novel electronic device for use in remote control systems of the type indicated above.

A further object of my invention is to provide a novel electromagnetic relay for use in such systems.

Other objects of my invention will become evident from the following detailed description taken in conjunction with the accompanying drawing in which:

Figure 1 is a diagrammatic view in perspective of an electronic device utilized in the practice of my invention.

Fig. 2 is a diagrammatic view of a remote control system embodying my invention.

Fig. 3 is a fragmentary elevational view of a modification of the electronic device shown in Fig. 1, and

Fig. 4 is a diagrammatic view of a remote control system employing the electronic device shown in Fig. 3.

Referring to Fig. 1 in detail, a base plate 1, of suitable insulating material, is provided for supporting an electronic device 2 and a magnetic system consisting of an L-shaped bar magnet 3 and an electromagnet 4.

The electronic device 2 may be secured to the base plate 1 by means of a socket pin connection of the usual type (not shown). The electromagnet 4 is secured at the midpoint of its magnetic circuit to the bar magnet 3 by any

suitable fastening means (not shown), and the latter is supported from the base plate 1 by any suitable means, such as a bracket 5.

The electronic device 2 comprises a sealed envelope 6 having a filling of a suitable gas such as neon or argon at low pressure, and a sealed-in stem 7 of glass which acts as a support for the electrode structure in the usual manner. A block 8, of magnetic material, is secured by means of a rigid support to the stem 7. The block 8 is centrally slotted to support a resilient reed 9 of magnetic material.

The reed 9 is centrally spaced between a pair of laminated pole tips 10 of magnetic material, the inner faces of which are provided with electrode plates 12 of suitable metal such as thorium. The pole tips 10 are supported by means of a suitable rigid supporting member 11 from the glass stem 7.

The block 8 is so positioned with reference to the bar magnet 3 as to provide a polarizing magnetic bias for the reed 9. The reed 9 is so spaced with reference to the electrode plates 12 that for the gas pressure existing in the envelope 6, and with normal voltage applied between the reed 9 and plates 12, no discharge takes place if the reed 9 is in its central position. However, if the reed 9 is vibrated from its central position, a discharge occurs to the nearest plate 12 which is interrupted at zero value of line voltage.

Referring to Fig. 2, the main power line is indicated at 13 and the source of superposed frequency currents at 14. It will be understood that the power line 13 may be an alternating current feeder or load circuit, and the source 14 may be located at any suitable point, such as a transformer sub-station.

The electronic device 2 is connected to energize a thermal relay 15, of special construction, for controlling the translating devices such as lamps 16.

The relay 15 comprises a pivoted armature 17 biased by means of a spring 18 to an open position as shown. The armature 17 may be attracted to a closed position, in which the translating devices 16 are connected to the main power circuit 13, by means of an electromagnet 19.

The armature 17 in its open position is arranged to maintain a bimetal spring 21 under tension. The bimetal spring 21, as shown, is normally straight and is arranged to be curled upward when heated for a sufficient length of time by a resistance heater 22. The bimetal spring 21, in its deenergized or straight position, is arranged to latch the armature 17 in its closed position.

tion. When heated, however, the bimetal spring 21 curls upward to a position clear of the armature 17, and permits the latter to fall open if the electromagnet 19 is deenergized.

5 The electromagnet 4, associated with the electronic device 2, is connected in series with a suitable condenser 23 to form a resonant circuit therewith having a natural frequency the same as that of the superposed carrier. The reed 9 of the electronic device 2 may also have the same natural period as the superposed carrier, or may have a natural frequency which is a harmonic or a sub-multiple of the superposed carrier frequency.

10 15 The operation of the apparatus shown in Fig. 2 may be set forth as follows: Upon operation of the transmitter 14 to supply carrier current to the line 13, the reed 9 commences to vibrate under action of the electromagnet 4. Upon vibration of the reed 9 the electronic device 2 becomes periodically conducting, and the discharge current thereof energizes the electromagnet 19 and the heater 22. Upon energization of the electromagnet 19, the armature 17 moves to its closed position, and the bimetal spring 21 snaps into its straight position latching the armature closed. A circuit is now completed for the translating devices 16. If the carrier frequency is discontinued after a short time interval, the bimetal spring 21 is not heated sufficiently to curl upward to its release position, and the armature 17 accordingly remains latched in its closed position.

20 25 When it is desired to disconnect the translating devices 16, the carrier currents are again applied for a much longer interval. Upon application of the carrier currents the electronic device 2 again becomes conducting, and the electromagnet 19 and heater 22 are energized from the line 13. As the armature 17 is already in its closed position, the energization of the electromagnet 13 has no effect. However, the heater 22 acts upon the bimetal spring 21, causing the latter to gradually curl up to a position in which it is clear of the armature 17. After a suitably long time interval, the carrier frequency currents are interrupted. This causes deenergization of the electromagnet 19, but the bimetal spring 21 remains in its upper position because of the heat stored in its own mass. The armature 17, accordingly, is moved to its open position by the spring 18. As the bimetal spring 21 cools it gradually descends to the position shown and remains under tension.

30 35 Referring to Fig. 3, the electronic device shown therein is provided with a flexible reed 9 as in Fig. 1. The reed 9 is spaced quite closely, how-

ever, to a pair of igniter elements 25, so that it may engage one or both of the latter upon vibration. A pair of pole tips 27 are mounted on either side of the magnetic reed 9. The pole tips 27 are arranged in the magnetic circuit of an external alternating current electromagnet 29. A cylindrical cathode 33 is supported in a position surrounding the reed 9 so as to complete a discharge path with the latter. In this modification no permanent magnetic bias is provided. 10

15 The igniter elements 25 are connected to an external inductance 31 in such manner as to complete a circuit through the latter upon their engagement with the reed 9. In this modification, upon vibration of the reed 9 a make-and-break connection is established through the inductance 31, and a high induced voltage is applied to a very short film of gas between the igniter element 25 and the reed 9. The electronic device, accordingly, becomes periodically ionized, and the main discharge takes place between the reed 9 and the cathode 33. The operation of the arrangement shown in Fig. 4 is otherwise the same as that of Fig. 2, and will be obvious from the above. 20

25 I do not intend that the present invention shall be restricted to the specific structural details, arrangement of parts or circuit connections herein set forth, as various modifications thereof may be effected without departing from the spirit and scope of my invention. I desire, therefore, that only such limitations shall be imposed as are indicated in the appended claim. 30

I claim as my invention:

35 An electronic device responsive to alternating currents comprising a sealed envelope having a gaseous medium therein, a pair of stationary principal electrodes in said envelope, a magnetic reed mounted in said envelope for vibratory movement along a path substantially perpendicular to the long axis of said reed, said magnetic reed having a principal electrode providing two anode-cathode discharge paths of variable effective length depending upon the position of said magnetic reed, electromagnetic means responsive to said alternating currents for vibrating said reed, 40 said electromagnetic means including an alternating current electromagnet external to said envelope but included in a magnetic circuit having an air gap portion traversing said magnetic reed substantially along said path, and unidirectional magnetic energizing means including a magnetic member external to said envelope and included in a second magnetic circuit, said second magnetic circuit having a portion substantially 45 following the long axis of said reed. 50
